United States Patent Office

Des. 214,354
Patented June 3, 1969

214,354

HANDLEBAR FOR A TWO-WHEELED VEHICLE OR THE LIKE

Sherwood B. Ross, 155 Woodmere Blvd.,
Woodsburgh, N.Y.

Filed Apr. 11, 1968, Ser. No. 11,413

Term of patent 14 years

Int. Cl. D12—11

U.S. Cl. D90—11

FIG. 2

FIG. 1

FIG. 3

FIG. 5

FIG. 4

FIGURE 1 is a perspective view of a handlebar for a two-wheeled vehicle or the like, showing my new design.

FIGURE 2 is a top plan view thereof.

FIGURE 3 is a front elevational view thereof.

FIGURE 4 is a rear elevational view thereof.

FIGURE 5 is a side elevational view thereof.

The elements of a bicycle, shown in broken lines, are included for illustrative purposes only.

I claim:

The ornamental design for a handlebar for a two-wheeled vehicle or the like, as shown and described.
